BABY'S EXERCISER

Robert Y. Allen and Melvin Shaw, Los Angeles, Calif.,
assignors to Hoover Products, Inc., Youngstown, Ohio,
a corporation of Ohio

Application April 29, 1957, Serial No. 45,936

Term of patent 3½ years

(Cl. D34—15)

The figure is a perspective view of the baby's exerciser, showing our new design.

The back of the baby's exerciser is substantially a mirror image of the front except for the heads which are plain.

We claim:

The ornamental design for a baby's exerciser, as shown and described.
